UNITED STATES PATENT OFFICE.

ANOSTOPULO D. THEODORE, OF EUNICE, LOUISIANA.

ARTICLE-DISPENSING DEVICE.

1,289,019.

Specification of Letters Patent. Patented Dec. 24, 1918.

Application filed June 15, 1918. Serial No. 240,268.

To all whom it may concern:

Be it known that I, ANOSTOPULO D. THEODORE, a citizen of the United States, residing at Eunice, in the parish of St. Landry

5 and State of Louisiana, have invented certain new and useful Improvements in Article-Dispensing Devices, of which the following is a specification, reference being had to the accompanying drawings.

10 This invention relates to an improved article dispensing device, and has for its primary object to provide simple and reliable means for singly delivering a single straw, match or like article from a hopper or container.

15 It is another and more particular object of the invention to provide a device for the above purpose having a container of inverted, triangular-shaped form, a plunger 20 longitudinally movable in the apex of the container, the end wall of the container having an opening therein through which the article is expelled in the movement of the plunger in one direction, and means for returning the plunger to its normal position.

25 It is another general object of my invention to provide a dispensing device of the above character, preferably having transparent side walls, and means adjustable upon the top of the container for holding or clamping a display card, glass bottle or other article.

With the above and other objects in view, the invention consists in the improved combination, construction and relative arrangement of the several parts as will be herein-after more fully described, subsequently claimed and illustrated in the accompanying drawing in which similar reference 35 characters designate corresponding parts throughout the several views, and wherein:

Figure 1 is a side elevation illustrating the preferred embodiment of my invention;

45 Fig. 2 is a longitudinal section;

Fig. 3 is a section taken on the line 3—3 of Fig. 2; and

Fig. 4 is a detail plan view.

Referring in detail to the drawing, 5 50 designates the downwardly converging, transparent walls of a substantially triangular-shaped receptacle or container. The end walls 6 and 7 to which said side walls are suitably secured are formed with suitable ornamental supporting feet 8. The end wall 7 has an opening 9 formed there-

through at the apex of the container which may be closed by means of the hinged plate 10 mounted upon the outer face of said end wall.

60 The other end wall 6 of the container is likewise provided with an opening 11 with which the bore of a guide sleeve 12, fixed to said end wall coincides. Above this guide sleeve an arm 13 is fixed in the end wall 6 and extends horizontally therefrom, and in the end of this arm an operating lever 14 is fulcrumed intermediate of its ends as shown at 15. The lower end of this lever is pivotally connected to the outer end of 70 a plunger rod 16, which is slidable through the guide sleeve 12. A coil spring 17 is arranged upon the plunger rod within the guide sleeve and bears at one of its ends against an internal shoulder 18 on said 75 sleeve and at its other end against an annular shoulder 19 formed on the plunger rod.

When straws or other similar articles are placed within the container, they gravitate 80 downwardly upon the sidewalls 5 into the apex thereof, so that a single one of the straws will find lodgment in the bottom of the container and in line with the openings 9 and 11 formed in the end walls thereof. 85 When it is desired to dispense a straw, the upper end of the operating lever is moved laterally in an outward direction and the plunger rod thereby forced inwardly 90 against the action of the spring 17. The 95 inner end of the plunger rod, moving through the opening 11, engages the end of the straw and forces the same longitudinally outwardly through the opening 9 in the other end wall of the container. Upon the release of the lever, the spring 17 immediately acts to return the plunger rod to its normal position.

20 designates the removable top for the container, which is provided on its longitudinal edges with inwardly inclined flanges 100 21 for sliding engagement with the outer face of the respective side walls 5. In the container top or cover, spaced pairs of bolts 22 are fixed, and upon said bolts the clamping nuts 23 are threaded.

24 designates article holding standards, which may be of any desired ornamental form, and each of these standards is provided at its lower end with an angular arm 110 25 having a slot 26 therein opening upon the end of the arm. These slots are adapted

to receive the upstanding bolts 22 in the top. The standards in each pair may be arranged in opposed parallel relation to each other and a display card, such as indicated at C, 5 then arranged between said standards. The standards are finally moved inwardly against the opposite sides of the card, and the nuts 23 adjusted into clamping engagement with the angular arms 25 so as to 10 securely clamp the standards against relative movement and hold the card in position, as seen in Fig. 2. The standards 24 can also be adjusted relative to each other for clamping engagement to the sides of a glass or bottle 15 which it may be desired to display. Various other articles can also be conveniently displayed upon the top 20 of the container and securely held in place by means of the adjustable standards.

20 From the foregoing description, taken in connection with the accompanying drawing, the construction, manner of use and several advantages of the invention will be clearly and fully understood. It will be seen that 25 the device is relatively simple, positive and reliable in its operation, and can also be manufactured at comparatively small cost. The container can, of course, be made in various sizes as may be determined in accordance with the length of the articles to 30 be dispensed. Various other elements of the device above referred to are likewise susceptible of considerable modification and it is,

therefore, to be understood that while I have herein shown and described the preferred embodiment of the device, it is nevertheless susceptible of considerable variation and I, therefore, reserve the privilege of adopting all such legitimate changes as may be fairly embodied within the spirit and scope of the 35 invention as claimed.

I claim:—

An article dispensing device including a container having convergently disposed side walls and end walls to which said side walls are fixed at their opposite ends, each of said end walls having an opening therein, a plunger at all times engaged in one of said 45 openings, a guide for the plunger fixed to one end wall, a spring coacting with the 50 guide and the plunger and urging the latter to its normal position, an arm fixed to the container wall and a manually operable lever pivoted upon the arm and operatively connected to said plunger to move the same inwardly through the opening against the action of said spring and project one of the 55 articles from the container through the opening in the other end wall thereof.

In testimony whereof I hereunto affix my 60 signature in the presence of two witnesses.

ANOSTOPULO D. THEODORE.
